TRAUGOTT GOLDE, OF PASSAIC, NEW JERSEY.

HINGED VEHICLE-HOOD.

1,034,906.

Specification of Letters Patent.

Patented Aug. 6, 1912.

Application filed February 15, 1912. Serial No. 677,710.

To all whom it may concern:

Be it known that I, TRAUGOTT GOLDE, a subject of the Prince of Reuss, Younger Line, residing at Passaic, in the county of 5 Passaic and State of New Jersey, have invented a new and Improved Hinged Vehicle-Hood, of which the following is a specification.

This invention relates to a vehicle hood of 10 novel construction for automobiles and other vehicles, which is adapted to sustain the foldable top in a firm and reliable manner.

In the accompanying drawing: Figure 1 is a side view of a vehicle hood embodying 15 my invention, showing it open, and Fig. 2 a similar view showing the hood folded.

The hood comprises a pair of rear bows 1 and 2 which are hinged to the carriage body at 3. To the foremost bow 2 there is hinged 20 at 4, the rear end of a forwardly extending arm 5, to the front end of which is connected by stop hinge 6 an outrigger bow 7. A diagonal brace 8 is hinged to bow 2 at a distance above pivot 4 as at 9, and to outrigger bow 7 at a distance in advance of 25 pivot 6, as at 10, so that in this way the outrigger bow is firmly supported. To arm 5 there is further hinged at 11, the lower end of an inclined intermediate bow 12, which 30 flanks brace 8 and is entirely disconnected therefrom, so that the brace and bow may freely swing in opposite directions when the device is folded or unfolded. This freedom

of movement is essential for the reason that the brace and bow are inclined in opposite 35 directions and intersect each other, so that in folding the hood, the front of the brace will swing downward while the front of the bow will swing upward.

To rear bows 1, 2 there are pivoted at 13, 40 14 a pair of auxiliary rear bows 15, 16, which are adapted to assume a vertical position intermediate bows 1 and 2 when the device is opened. These auxiliary bows 15, 16 as well as all the other bows, 1, 2, 7, 12 are of 45 course connected to the foldable top.

It will be seen that my improved vehicle hood is simple in construction, readily foldable and that it is well adapted to efficiently support the top.

I claim:

A vehicle hood comprising a rear bow, a forwardly extending arm pivoted thereto, an outrigger bow pivoted to the arm, a downwardly inclined diagonal brace connecting the rear bow at a distance above the arm to the outrigger bow, and an intermediate upwardly inclined bow pivoted to the arm, said intermediate bow crossing the diagonal brace and being disconnected therefrom, whereby said bow and brace are foldable in opposite directions.

TRAUGOTT GOLDE.
